INTERNAL COMBUSTION ENGINE.
APPLICATION FILED APR. 10, 1912.

Patented Apr. 21, 1914.

2 SHEETS-SHEET 1.

UNITED STATES PATENT OFFICE.

FREDERIC S. THORNLEY, OF CLARION, IOWA.

INTERNAL-COMBUSTION ENGINE.

1,093,659.

Specification of Letters Patent. Patented Apr. 21, 1914.

Application filed April 10, 1912. Serial No. 689,749.

To all whom it may concern:

Be it known that I, FREDERIC S. THORNLEY, a citizen of the United States, residing at Clarion, in the county of Wright and State of Iowa, have invented a new and useful Internal-Combustion Engine, of which the following is a specification.

The present invention relates to improvements in internal combustion engines, the primary object of the invention being the provision of an internal combustion engine, the power piston of which is provided with intake and exhaust ports in the head and through the opposite walls thereof that are controlled by a rotary valve disposed above and in operative relation to the ports of the head and controlled through the operation of the crank shaft to permit of the proper timing of the intake of the explosive charge and the exhaust of the burnt gases, the cylinder in which the power piston is mounted being provided with oppositely disposed intake and exhaust ports positioned so as to be at the lowest point of the stroke, whereby the piston is permitted the full stroke of the cylinder during compression to compress the explosive charge in the smallest possible space, the exhaust taking place after the piston has reached its fullest in-stroke position and has started upon its out-stroke, thus securing from the explosive charge the maximum amount of power.

A further object of the present invention is the provision of a scraping or cleaning device operated simultaneously with the rotary valve to remove the adhering carbon from the end of the piston.

A still further object of the present invention is the provision of a novel form of valve actuating means disposed concentrically of the power piston and journaled within the piston rod, a universal joint and adjusting means being provided to permit of the proper adjustment of the rotary valve in order that it may be operated in time with the movements of the power piston.

A still further object of the invention is the provision of a splash lubricating means disposed concentrically of the operating mechanism for the rotary valve for receiving the lubricant at the lower portion of the crank case and directing it to the upper and lower faces of the rotary valve to insure the proper lubrication thereof.

With the foregoing and other objects in view which will appear as the description

proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a transverse vertical sectional view through a single cylinder of the internal combustion engine made according to and embodying the present invention, the power piston being in its lowermost position. Fig. 2 is a similar view with the piston in its highest position. Fig. 3 is a similar view to Fig. 1 taken at right angles thereto. Fig. 4 is an enlarged detail sectional view through the cylinder and the head portion of the power piston. Fig. 5 is a cross section taken on line 5—5 of Fig. 1. Fig. 6 is a perspective view of the carbon removing scraper. Fig. 7 is an enlarged detail view of the universal joint coupling for the rotary valve actuating rod. Fig. 8 is an enlarged detail sectional view of the lower end of the rotary valve operating rod. Fig. 9 is an enlarged detail view of the main piston rod connection with the crank shaft, showing the gear for actuating the rotary valve. Fig. 10 is a perspective view of the piston, with the retaining disk and rotary valve removed. Fig. 11 is a top plan view of the piston minus the disk and valve. Fig. 12 is a perspective view of the retaining disk. Fig. 13 is a perspective view of the rotary valve.

Referring to the drawings, the numeral 1 designates the crank case and base of the engine, which forms a reservoir for the lubricant of a splash lubricating system, and has journaled therein, the crank shaft 2 which has operably connected thereto the piston rod 3, said piston rod 3 being provided near the upper end thereof with the inclined bore 4 which is disposed at an angle so as to terminate in a recess near the lower end of the piston rod and form a journal for the valve actuating rod 5 whose lower end 5' is provided with the toothed portion 6, whereby the said lower end may be adjusted to regulate the timing of the valve 13 controlled by said rod 5, as will presently appear. The band 3' is connected to the piston rod 3 at its connection with the crank shaft and forms a lower journal for the valve actuating rod 5. A worm gear 7 is keyed to the

lower end 5' of the valve actuating rod and is in mesh with the gear 8 turned upon the crank shaft, as clearly shown in Figs. 1 and 8. Thus it will be seen that the rotation of the crank shaft will impart through the worm gears 8 and 7 the proper rotation to the valve actuating rod or shaft 5.

The upper end of the valve actuating rod 5 is connected by means of the universal joint 10, which is disposed in line with the pin 3^a, for connecting the piston rod 3 to the power piston, to the valve 13. The universal joint 10 connects the upper end of the shaft 5 to the lower end of the valve carrying stem 11, which is journaled in the concentric sleeve 15 of the power piston 14 and carries upon its upper end the concaved rotary disk valve 13, which is disposed in the recess 15' formed in the head 16 of the piston 14, the annular rim 17 providing a proper seat for the rotary disk valve 13 and co-acting with the retaining concaved disk 18 to properly position and retain the rotary valve 13 relatively to the power piston. The head 16 and retaining disk 18 are provided with aligned exhaust ports 24—24' and the intake ports 25—25', while the rotary valve 13 is provided with a single port 26 which is adapted to be placed in registration with the respective ports 24—24' and 25—25', in proper time with the reciprocation of the power piston 14. The disk 18 is properly secured to the power piston 14 by means of screws or other fastening means, such as 19, so as to permit of ready access to the rotary valve 13, as clearly shown in Fig. 4.

In the concentric bore 20 of the retaining disk 18, is disposed a sleeve or bushing 21, the same being mounted so as to rotate with the screw 22 which secures the bushing 21 to the valve stem 11 upon the upper side of the valve 13. This bushing 21 carries the scraper arm or blade 23 which is curved to conform to the upper surface of the retaining disk 18, so that when rotated any carbon that may adhere to the upper surface of the retaining disk 18 will be scraped therefrom to be finally ejected through the exhaust ports 24 and 24' of the disk 18 and valve head 16.

Formed in the walls of the power piston 14 are the respective exhaust and inlet recesses 24^a and 25^a, the same being so disposed as to permit of the proper admission of the explosive charge through the intake port 27 into the intake recess 25^a of the power piston and finally through the ports 25', 26 and 25 into the explosive chamber of the cylinder C.

The rotary valve 13 is so timed that the registration just mentioned will take place upon the down stroke of the piston 14 so as to insure of the proper passage of the explosive charge within the chamber of the cylinder C so that upon the up or compression stroke, the charge will be properly compressed and will not be forced into any aux-

iliary chamber, as is usually the case where puppet valves are employed. The rotary valve 13 is so timed that the exhaust does not take place until the piston has been moved to its lowest point and has started upon the up stroke at which time the ports 24, 26 and 24' are placed in registration and the burnt gases are ejected through the exhaust recess 24^a into the exhaust manifold 28 of the cylinder.

The cylinder C is provided with the water jacket J the full length thereof and has mounted in its upper end the spark plug S.

As the rotary valve 13 is practically incased in the upper end of the power piston 14, it is necessary that the stem 11 and that the upper and under surfaces of the valve be properly lubricated, and in order to accomplish this in an efficient manner to prevent any binding whatsoever, a feed spout 9 is disposed at the lower end of the member 5' of the valve actuating rod, the same being carried by the locking plug or sleeve 29 which is provided with a concentric bore 30 terminating in the valve seat 31 controlled by a ball valve 32 within the chamber formed in the lower end of the shaft 5. The shaft 5 is provided with the lubricant conveying bore 9' the full length thereof which leads into the lower end of the bore 9" of the valve stem 11. The upper end of the bore 9" terminates in the respective branches a, b and c, the branch a conveying the lubricant to lubricate the stem 11 and the inner wall of the sleeve 15 of the power piston 14, while the branch b conveys the lubricant to the under side of the retaining disk 18 and consequently the upper side of the rotary valve 13. The branch c directs the lubricant between the under surface of the valve 13 and the recess formed in the head of the cylinder 14. The valve 32 will act as a check valve to prevent the lubricant from flowing back into the bore 30 of the locking sleeve 29, and thus insure the proper feeding of the lubricant to the rotary valve 13, while the outer wall of the piston 14 provided with the packing rings d and e will be properly lubricated from the splash, due to the crank shaft entering the lubricant within the crank case of the engine. A guiding spout or lip 33 is formed upon the lower end of the piston rod 3 to direct the lubricant to the worm gears 8 and 7, as clearly shown in Figs. 1 and 9.

By means of the locking sleeve 29, the same may be removed from connection with the lower end of the shaft 5 so as to release the lower section 5' of the shaft and permit the lower section to be rotated to properly adjust the worm 7 with relation to the port 26 of the valve 13, thus insuring a means whereby the port 26 will be always in proper time with the reciprocations of the piston, so that the explosive charge will be taken

into the explosive chamber of the cylinder at the proper time, and the burnt charges be exhausted therefrom also in proper time.

In order to vary the explosive chamber area, by increasing or decreasing the length of the cylinder C, and consequently vary the compressive action of the piston, the metal gasket 40, which may be made of varying heights, is insertible between the body 10 and head of the cylinder.

From the foregoing description taken in connection with the drawings, the operation of the present internal combustion engine is readily understood, but briefly stated it is 15 as follows: Assuming the piston 14 to be in the position as shown in Fig. 1, the engine will be cranked or rotated in the direction of the arrow Fig. 1 and thus move the piston upwardly, the port 26 at this time being in 20 registration with the exhaust ports 24-24' so that there will be practically no compression within the cylinder. Upon the continued rotation of the crank shaft, the piston 14 will be moved downwardly, at 25 which point the port 26 will be brought into overlapping registration with the ports 25 and 25' so that an explosive charge will be taken into the cylinder during the down stroke, at which time the port 26 will have 30 passed beyond the ports 25 and 25' closing the explosive chamber to permit of the proper compression of the charge within the chamber. At the highest point of compression, the charge will be exploded and 35 the piston will be moved downwardly, and when just reaching its lowest point and starting upon its up-stroke, the port 26 will have been moved into overlapping registration with the ports 24 and 24' to permit 40 of the burnt gases exhausting therethrough and from the recess 24^a into the exhaust port 28. This registration continues until the piston has traveled upwardly again, thus 45 insuring the proper expulsion of the burnt gases from the explosive chamber and previous to the intake of the explosive charge through the intake port 27.

What is claimed is:

1. An internal combustion engine, having a crank case, a cylinder with oppositely disposed intake and exhaust ports intermediate of its ends, a crank shaft, a power piston mounted in the cylinder and operably connected to the crank shaft, said piston having two oppositely disposed recesses in its walls and two ports in its head, a rotary valve having a single port mounted in the head of the piston for controlling the ports thereof, and means operably connecting said valve with the crank shaft.

2. An internal combustion engine, having a crank case, a cylinder provided with an intake and an exhaust port, a crank shaft, a power piston mounted in the cylinder and 65 operably connected to the crank shaft, said

piston being provided with an intake and an exhaust port, a rotary valve carried by the piston and having a single port disposed for registration with the respective intake and exhaust ports of the piston, and means operably connecting said valve with the crank shaft.

3. An internal combustion engine, having a crank case, a cylinder provided with an intake and an exhaust port, a crank shaft, a power piston mounted in the cylinder and operably connected to the crank shaft, said piston being provided with an intake and an exhaust port, a rotary valve carried by the piston and having a single port disposed for registration with the respective intake and exhaust ports of the piston, and means carried by the piston, and piston rod, and operated from the crank shaft for operating the valve.

4. An internal combustion engine, having a crank case, a cylinder provided with an intake and an exhaust port, a crank shaft, a power piston mounted in the cylinder, a rod operably connecting the power piston to the crank shaft, said power piston being provided with an intake and an exhaust port therein, a rotary valve having a single port carried by the power piston, and means journaled in the piston rod and operably connected to the crank shaft and valve for actuating the valve to control the intake and exhaust ports of the piston.

5. An internal combustion engine, having a crank case, a cylinder provided with an intake and an exhaust port, a crank shaft, a power piston mounted in the cylinder, a rod operably connecting the power piston to the crank shaft, said power piston being provided with an intake and an exhaust port therein, a rotary valve having a single port carried by the power piston, and a shaft journaled in the piston rod, said shaft having its lower end operably connected to the crank shaft and its upper end operably connected to the rotary valve, whereby the rotary valve is actuated from the crank shaft.

6. An internal combustion engine, having a crank case, a cylinder with oppositely disposed intake and exhaust ports intermediate of its ends, a crank shaft, a power piston mounted in the cylinder and operably connected to the crank shaft, said piston having two oppositely disposed recesses in its walls and two ports in its head, a rotary valve having a single port mounted in the head of the piston for controlling the ports thereof, means for operably connecting said valve with the crank shaft, and means for scraping the upper surface of the power piston operably connected to and actuated simultaneously with the rotary valve.

7. An internal combustion engine, having a crank case, a cylinder provided with an intake and an exhaust port, a crank shaft, a

power piston mounted in the cylinder and operably connected to the crank shaft, said piston being provided with an intake and an exhaust port, a rotary valve having a single port mounted in the piston and disposed for registration with the respective intake and exhaust ports of the piston, means operably connecting said valve with the crank shaft, and means for scraping the upper surface of the power piston operably connected to and actuated simultaneously with the rotary valve.

8. An internal combustion engine, having a crank case, a cylinder provided with an intake and an exhaust port, a crank shaft, a power piston mounted in the cylinder and operably connected to the crank shaft, said piston being provided with an intake and an exhaust port, a rotary valve having a single port mounted in the piston and disposed for registration with the respective intake and exhaust ports of the piston, means carried by the piston, and piston rod, and operated from the crank shaft for operating the valve, and means for scraping the upper surface of the power piston operably connected to and actuated simultaneously with the rotary valve.

9. An internal combustion engine, having a crank case, a cylinder provided with an intake and an exhaust port, a crank shaft, a power piston mounted in the cylinder, a rod operably connecting the power piston to the crank shaft, said power piston being provided with an intake and an exhaust port therein, a rotary valve having a single port carried by the power piston, means journaled in the piston rod and operably connected to the crank shaft and valve for actuating the valve to control the intake and exhaust ports of the piston, and means for scraping the upper surface of the power piston operably connected to and actuated simultaneously with the rotary valve.

10. An internal combustion engine, having a crank case, a cylinder provided with an intake and an exhaust port, a crank shaft, a power piston mounted in the cylinder, a rod operably connecting the power piston to the crank shaft, said power piston being provided with an intake and an exhaust port therein, a rotary valve having a single port carried by the power piston, a shaft journaled in the piston rod, said shaft having its lower end operably connected to the crank shaft and its upper end operably connected to the rotary valve, whereby the rotary valve is actuated from the crank shaft, and means for scraping the upper surface of the power piston operably connected to and actuated simultaneously with the rotary valve.

11. An internal combustion engine, having a crank case, a cylinder with oppositely disposed intake and exhaust ports intermediate of its ends, a crank shaft, a power

piston mounted in the cylinder and operably connected to the crank shaft, said piston having two oppositely disposed recesses in its walls and two ports in its head, a rotary valve having a single port mounted in the head of the piston for controlling the ports thereof, means operably connecting said valve with the crank shaft, and means for conducting a lubricant from the crank case to the rotary valve.

12. An internal combustion engine, having a crank case, a cylinder provided with an intake and an exhaust port, a crank shaft, a power piston mounted in the cylinder and operably connected to the crank shaft, said piston being provided with an intake and an exhaust port, a rotary valve having a single port mounted in the piston and disposed for registration with the respective intake and exhaust ports of the piston, means operably connecting said valve with the crank shaft, and means for conducting a lubricant from the crank case to the rotary valve.

13. An internal combustion engine, having a crank case, a cylinder provided with an intake and an exhaust port, a crank shaft, a power piston mounted in the cylinder and operably connected to the crank shaft, said piston being provided with an intake and an exhaust port, a rotary valve having a single port mounted in the piston and disposed for registration with the respective intake and exhaust ports of the piston, means carried by the piston, piston rod, and operated from the crank shaft for operating the valve, and means for conducting a lubricant from the crank case to the rotary valve.

14. An internal combustion engine, having a crank case, a cylinder provided with an intake and an exhaust port, a crank shaft, a power piston mounted in the cylinder, a rod operably connecting the power piston to the crank shaft, said power piston being provided with an intake and an exhaust port therein, a rotary valve having a single port carried by the power piston, means journaled in the piston rod and operably connected to the crank shaft and valve for actuating the valve to control the intake and exhaust ports of the piston, and means for conducting a lubricant from the crank case to the rotary valve.

15. An internal combustion engine, having a crank case, a cylinder provided with an intake and an exhaust port, a crank shaft, a power piston mounted in the cylinder, a rod operably connecting the power piston to the crank shaft, said power piston being provided with an intake and an exhaust port therein, a rotary valve having a single port carried by the power piston, a shaft journaled in the piston rod, said shaft having its lower end operably connected to the crank shaft and its upper end operably connected to the rotary valve, whereby

the rotary valve is actuated from the crank shaft, and means for conducting a lubricant from the crank case to the rotary valve.

16. An internal combustion engine, having a base, a crank shaft, a piston rod, a cylinder, said cylinder having intake and exhaust ports, a power piston mounted in the cylinder and connected to the piston rod, a rotary disk valve having a stem mounted 10 concentrically of the upper end of the power piston, said rotary disk valve being provided with a single port, said power piston being provided with an intake and exhaust port controlled by the port of the rotary 15 valve, and means connected to the crank shaft and to the concentric stem of the rotary valve for actuating the valve from the crank shaft.

17. An internal combustion engine, having a base, a crank shaft, a piston rod, a cylinder, said cylinder having intake and exhaust ports, a power piston mounted in the cylinder and connected to the piston rod, a rotary disk valve having a stem mounted 25 concentrically of the upper end of the power piston, said rotary disk valve being provided with a single port, said power piston being provided with an intake and an exhaust port controlled by the port of the rotary 30 valve, a shaft journaled in the piston rod, a universal joint connecting the upper end of the shaft to the lower end of the valve stem, and coacting means carried by the lower end of said shaft and the crank shaft 35 for operating said shaft and the rotary valve from the crank shaft.

18. An internal combustion engine, having a base, a crank shaft, a piston rod, a cylinder, said cylinder having intake and 40 exhaust ports, a power piston mounted in the cylinder and connected to the piston rod, a rotary disk valve having a stem mounted concentrically of the upper end of the power piston, said rotary disk valve being provided 45 with a single port, said power piston being provided with an intake and exhaust port controlled by the port of the rotary valve, a shaft journaled in the piston rod, a universal joint connecting the upper end of 50 the shaft to the lower end of the valve stem, the lower end of said shaft being detachable and adjustable to regulate the timing of the rotary valve with the reciprocation of the power piston, and coacting means carried 55 by the lower end of said shaft and the crank shaft for operably connecting the rotary valve to the crank shaft.

19. An internal combustion engine, having a cylinder, and a power piston mounted 60 for reciprocation therein, said power piston having a concaved recessed portion in the head thereof and a concentric bore leading therefrom, said power piston being provided with intake and exhaust ports through the 65 head thereof, a concaved disk valve mounted

in the recess of the piston head and provided with a concentric stem disposed for rotation within the concentric bore of the power piston, said rotary valve being provided with a single port, and a retaining 70 disk connected to the power piston above the rotary valve and provided with intake and exhaust ports in registration with the respective intake and exhaust ports of the power piston.

20. An internal combustion engine, having a cylinder, and a power piston mounted for reciprocation therein, said power piston having a concaved recessed portion in the head thereof and a concentric bore leading therefrom, said power piston being provided with intake and exhaust ports through the head thereof, a concaved disk valve mounted in the recess of the piston head and provided with a concentric stem disposed for rotation 85 within the concentric bore of the power piston, said rotary valve being provided with a single port, a piston rod connected to the power piston, a crank shaft operably connected to the piston rod, a shaft journaled in the piston rod, a universal joint connecting the upper end of the shaft to the lower end of the rotary valve stem, and coacting means carried upon the lower end of said shaft and the crank shaft for operating the rotary 95 valve.

21. An internal combustion engine, having a cylinder, and a power piston mounted for reciprocation therein, said power piston having a concaved recessed portion in the head thereof, and a concentric bore leading therefrom, said power piston being provided with intake and exhaust ports through the head thereof, a concaved disk valve mounted in the recess of the piston head and provided with a concentric stem disposed for rotation 100 within the concentric bore of the power piston, said rotary valve being provided with a single port, a piston rod connected to the power piston, a crank shaft operably connected to the piston rod, a shaft journaled in the piston rod, a universal joint connecting the upper end of the shaft to the lower end of the rotary valve stem, and coacting means carried upon the lower end of said shaft and the crank shaft for operating the 105 rotary valve, said shaft and valve stem being provided with lubricant conveying ducts for lubricating the upper and lower surfaces of the rotary valve and the stem thereof.

22. An internal combustion engine, having a cylinder, and a power piston mounted for reciprocation therein, said power piston having a concaved recessed portion in the head thereof, and a concentric bore leading 110 therefrom, said power piston being provided with intake and exhaust ports through the head thereof, a concaved disk valve mounted in the recess of the piston head and provided with a concentric stem disposed for 115

rotating within the concentric bore of the power piston, said rotary valve being provided with a single port, a retaining disk secured to the piston head and over the valve, a piston rod connected to the power piston, a crank shaft operably connected to the piston rod, a shaft journaled in the piston rod, a universal joint connecting the upper end of the shaft to the lower end of the rotary valve stem, coating means carried upon the lower end of said shaft and the crank shaft for operating the rotary valve, said shaft and valve stem being provided with lubricant conveying ducts for lubricating the upper and lower surfaces of the rotary valve and the stem thereof, and a scraper blade connected to the rotary valve and operated simultaneously therewith for scraping the upper surface of the retaining disk.

23. An internal combustion engine, having a cylinder, and a power piston mounted for

reciprocation therein, said power piston having a recessed portion in the head thereof and a concentric bore leading therefrom, said power piston being provided with intake and exhaust ports through the head thereof, a disk valve mounted in the recess of the piston head and provided with a concentric stem disposed for rotation within the concentric bore of the power piston, said rotary valve being provided with a single port, and a retaining disk connected to the power piston above the rotary valve and provided with intake and exhaust ports in registration with the respective intake and exhaust ports of the power piston.

In testimony that I claim the foregoing as my own, I have hereto affixed my signature in the presence of two witnesses.
